UNITED STATES PATENT OFFICE

JOHN FREDERICK COMAN, OF NEW YORK, N. Y., ASSIGNOR TO ADAM HAT STORES, INC.,
OF NEW YORK, N. Y., A CORPORATION OF NEW YORK

DESIGN FOR A STORE FRONT

Application filed August 22, 1931. Serial No. 40,909. Term of patent 7 years.

To all whom it may concern:

Be it known that I, JOHN FREDERICK COMAN, a citizen of the United States, residing at 126 East 27th Street, in the county of New York and State of New York, have invented a new, original, and ornamental Design for a Store Front, of which the following is a specification, reference being had to the accompanying drawings, forming part thereof.

Figure 1 is a plan view of the store front and Figure 2 is a side view of the said store front showing my new design. Figure 1 is shaded to show contrasting colors.

I claim:

The ornamental design for a store front, as shown and described.

JOHN FREDERICK COMAN.
